BAFFLE FOR A COMBINATION LOUD SPEAKER, VENTILATOR, AND LIGHTING FIXTURE

Josef J. Hammes, Maplewood, Mo., assignor to
Benjamin W. Lowell, St. Louis County, Mo.

Filed Aug. 12, 1963, Ser. No. 76,173

Term of patent 14 years

(Cl. D62—4)

FIGURE 1 is a front perspective view of a baffle for a combination loud speaker, ventilator, and lighting fixture, showing my new design;

FIGURE 2 is a top plan view;

FIGURE 3 is a bottom plan view;

FIGURE 4 is a side elevational view; and

FIGURE 5 is a view in section taken on line 5—5 of FIGURE 3.

I claim:

The ornamental design for a baffle for a combination loud speaker, ventilator, and lighting fixture, as shown.
